PORTABLE PUBLIC ADDRESS SYSTEM

Donovan D. Hunt, Louisville, Ky.

Application May 22, 1953, Serial No. 356,829

9 Claims. (Cl. 179—1)

1

This invention relates to a novel supporting structure for a public address system and more particularly to a supporting structure adapted to be worn by the user for supporting a public address system including a self-contained current source to thereby provide an apparatus of extremely simple construction affording a complete portable public address unit which may be employed anywhere and wherein the user is free to move at will from place to place without limitation as to distance while using the apparatus.

More particularly, it is an aim of the present invention to provide a portable public address system especially adapted for use in warehouse and outdoor auctioneering and elsewhere where electric current is not available, and which may also be effectively used for numerous other purposes such as outdoor lecturing and teaching.

A further object of the invention is to provide a portable public address system which will comfortably and conveniently fit the body of the user, which is extremely light in weight and durable and which may be conveniently utilized for long periods of time without being a burden to the user and without straining the voice.

Numerous other objects and advantages of the invention will hereinafter become more fully apparent from the following description of the drawings, illustrating a presently preferred embodiment thereof, and wherein:

Figure 1 is a front elevational view of the complete apparatus;

Figure 2 is a side elevational view thereof looking from left to right of Figure 1;

Figure 3 is a horizontal sectional view taken substantially along a plane as indicated by the line 3—3 of Figure 1 and on an enlarged scale;

Figure 4 is an enlarged fragmentary horizontal sectional view taken substantially along a plane as indicated by the line 4—4 of Figure 1;

Figure 5 is a fragmentary cross sectional view on an enlarged scale, taken substantially along a plane as indicated by the line 5—5 of Figure 3;

Figure 6 is an enlarged horizontal sectional view taken substantially along a plane as indicated by the line 6—6 of Figure 1;

Figure 7 is an enlarged fragmentary vertical sectional view taken substantially along a plane as indicated by the line 7—7 of Figure 2;

Figure 8 is a diagrammatic view of the public address system;

Figure 9 is an enlarged fragmentary vertical sectional view taken substantially along a plane as indicated by the line 9—9 of Figure 1;

Figure 10 is an enlarged fragmentary vertical sectional view taken substantially along a plane as indicated by the line 10—10 of Figure 1;

Figure 11 is an enlarged fragmentary vertical sectional view taken substantially along a plane as indicated by the line 11—11 of Figure 1, and

2

Figure 12 is an enlarged fragmentary horizontal sectional view taken substantially along a plane as indicated by the line 12—12 of Figure 1.

Referring more specifically to the drawings, the portable, self-contained public address system in its entirety and comprising the invention is designated generally 15 and includes a harness, designated generally 16, which is detachably secured to the upper portion of the body of the user and supported thereon.

As best seen in Figures 3 and 5, the body engaging harness 16 includes a lower waist circling portion, designated generally 17, including a section 18 which engages across the back and along the sides of the body and which is shaped for conformably fitting said body portions. As seen in Figure 5, the section 18 preferably includes a strap formed of an outer ply 19 and an inner ply 20. Said plies are preferably formed of leather and suitably secured together adjacent their longitudinal edges as by stitching, as indicated at 21. The inner ply 20 is of sufficient width, relatively to the width of the outer ply 19, so as to be bulged away from said outer ply to accommodate therebetween a reinforcing bar 22 which is preferably formed of a substantially rigid metal or similar material. The bar 22 is disposed against the inner side of the outer ply 19 and the section 18 additionally includes suitable padding 23 disposed between the plies 19 and 20 and particularly between the inner ply 20 and the reinforcing bar 22. The waist circling member 17 also includes a flexible strap 24 one end of which is secured to an end of the member 18 by a suitable fastening 25. A buckle 26 is secured to the other end of the strap 24. A second strap 27 is secured at one end by a fastening 28 to the other end of said section 18 and the other, free end thereof is connected in a conventional manner to the buckle 26.

A pair of side brace bars 29 are secured to the side portions of the section 18 near the ends thereof by fastenings 30. Said side brace bars extend upwardly from the section 18 and are inwardly bowed, as illustrated in Figure 1. The side brace bars 29 are enclosed in sheaths or coverings 31, preferably formed of leather and containing padding 32 between an inner ply 33 of each sheath 31 and the bar 29. The sheaths 31 extend from the upper ends of said brace bars 29 downwardly to adjacent the section 18. A pair of substantially rigid supporting bars 34 are secured at their lower ends by fastenings 35 to the intermediate, rear portion of the section 18 and extend upwardly therefrom and are provided with inwardly bowed portions, as best illustrated in Figure 2, which are enclosed in casings or sheaths 36 which additionally contain padding 37, located between the inwardly bowed portions of the bars 34 and the inner plies 38 of said

sheaths. The sheaths 31 and 36 are preferably formed of flexible material such as leather and the padding 32 and 37 and likewise the padding 23 provide a cushioning contact between the harness portions and the body of the wearer. As best seen in Figure 1, the upper end portions of the supporting bars 34 are flared outwardly with respect to one another above the sheaths 36. A short length of pipe or tubing 39 has the end portions thereof clamped between the upper end of the supporting bars 34 and a pair of clamp sections 40 which are secured to said bars 34 above and below the pipe 39 by adjustable nut and bolt fastenings 41, as best illustrated in Figure 9. A pair of metal braces 42 are secured at their upper ends to the bars 34 between the upper ends of the sheaths 36 and the lower ends of the clamps 40, and the lower ends of said brace bars 42 are secured to the side brace bars 29, beneath and adjacent the sheaths 31. The brace bars 42 are bowed outwardly to engage around the sides and back of the harness wearer.

A pair of shoulder straps 43 have complementary loop ends 44 which are attached around the pipe or tubing 39, near the ends thereof and said straps 43 extend forwardly over the shoulders of the wearer and are provided with buckles 45 at the opposite ends thereof which are disposed over the chest and adjustably secured to the upper ends of a pair of front straps 46, constituting lower sections of the shoulder straps 43. The front straps 46 have looped lower ends 47 through which the straps 24 and 27 extend.

A small instrument panel 48 is demountably supported in front of the body of the user by a pair of short straps 49 which are connected to and extend from the ends of the panel 48 and which have eyes or slits 50 to detachably engage buttons 51, carried by the straps 46. A conventional amplifying unit 52 has hanger loops 53 attached thereto and extending upwardly therefrom. The loops 53 detachably engage hooks 54 which are pivotally supported as seen at 55 in Figure 10 on the pipe 39. The parts 53 and 54 constitute a part of the present invention and constitute a ready means for demountably supporting the amplifier 52 on the harness 16.

A tubular supporting standard 56 has a lower end which rests on the intermediate portion of the pipe 39 and is secured thereto by a metal strap member 57 and nut and bolt fastenings 58, as best illustrated in Figure 11. The standard 56 has a forwardly turned upper end 59 which is disposed at a sufficient height, as illustrated in Figures 1 and 2, to readily clear the head of a person wearing the harness 16. The portion 59 has a partially flat upper portion 60 to be received in the bifurcated lower end of a rigid link member, designated generally 61. A bolt 62 extends through the furcations of the bifurcated link portion 63 and through the standard portion 60 for pivotally mounting the link for swinging movement in a vertical plane on said standard. The bolt 62 is engaged by a wing nut 64 which is tightened to clamp the link 61 in different adjusted positions to the standard portion 60. A strap loop 65 is disposed around and secured to a portion of a conventional loud speaker 66 and has a downwardly offset bottom portion 67 which is disposed above and supported on a top portion 68 of the link 61. A double headed pin or rivet 69 forms a swivel connection between the portions 67 and 68 so that the loud speaker 66 may be swung in a complete circle about the link 61 and relatively to the standard 56 and may be

5
10
15

rocked with said link 61 either upwardly or downwardly in a vertical plane so that the enlarged open end of the loud speaker 66 may be disposed to face in any direction. A friction washer 70 is interposed between the portions 67 and 68 to prevent the loud speaker from swiveling freely about the link 61 and so that said loud speaker may be maintained in any desired position relatively to the standard 56.

10
15
20
25
30
35
40
45

A conventional microphone 71 is attached to one end of a resilient neck engaging band 72 which forms an open loop which is suspended loosely around the neck of the user. The ends of the resilient loop 72 are adapted to bear against the chest so that the microphone 71 may be readily supported by one of said ends, and the loop 72 may be readily removed from the neck when desired by merely spreading the ends thereof.

Suitably encased electrical conductors 73 extend between and connect the amplifier 52 to the loud speaker 66, said conductors 73 passing through a portion of the pipe 39 and through the tubular standard 56. A plug 74 attached to complementary ends of the conductors 73 forms a detachable electrical connection with the amplifying unit 52. Similarly, two conductors 75 extend between the amplifier 52 and the microphone 71, said conductors likewise being preferably enclosed in a casing of electrical insulating material and being connected at complementary ends thereof to a plug 76 which is detachably connected to the amplifier 52. Two posts 77 are mounted on the panel 48 to which are detachably connected complementary ends of a pair of conductors 78 and 79 which lead from the positive and negative terminals of a self-contained source of electric current such as a battery 80. Conductors 81 and 82 which are connected to the posts 77 and electrically connected through said posts to the conductors 78 and 79, respectively, lead from the posts 77 and are connected at their opposite ends to the amplifier 52 for supplying electric current thereto. The conductor 81 has a make and break electric switch 83 interposed therein and which is mounted on the panel 48. A volume control of a conventional construction, designated 84, is mounted on the panel 48 and connected by the wiring 85 to the amplifier 52.

50
55
60
65

The battery 80 is provided with loops 86 on opposite sides thereof to which looped ends 87 of a carrying strap 88 is detachably connected, as illustrated in Figures 1 and 2. The loops 87 are formed by a button and eye connection 89, corresponding to the connections 50, 51 so that the loops 87 may be opened for disengaging the strap 88 from the battery 80 to replace the battery, and one of the loops 87 may be opened for easily removing the battery 80 and strap 88 from its supported position of Figures 1 and 2. As shown in these figures, the strap 88 engages around the standard 56 for supporting the battery 80 at one side of the harness 16 and said strap is applied to the standard 56 after the harness has been secured on the wearer and is removed therefrom before removal of the harness, so that the weight of the battery 80 will not interfere with applying and removing the harness.

It will be readily apparent that the amplifying unit 52 may be readily attached to the harness 16 by engaging the hooks 54 with the loops 53. The plugs 74 and 76 may then be connected to the amplifying unit for connecting the loud speaker 66 and microphone 71 respectively thereto. The arms of the user may then be slipped outwardly through the shoulder straps 43 after which the

straps 24 and 27 may be adjustably connected by the buckle 28 around the waist of the user and, if necessary, the straps 46 may be adjusted by means of the buckles 65. The slits 50 may then be engaged with the buttons 51 for attaching the straps 49 to the straps 46 for mounting the front panel 48 across the front of the body of the wearer, after which the battery supporting straps 38 may be passed around the standard 56 and attached by its loops 67 to the battery loops 36. The two conductors 78 and 79 leading from the battery 98 may then be attached to the panel posts 77. The loop 72 is then engaged about the neck and the portable amplifying unit 16 is then ready for use and is put in use by moving the switch 83 to a circuit closing position and turning the knob of the volume control 84 to the desired volume. With the loud speaker 66 adjusted to a desired position, as previously described, the user may walk about to any distance while talking over the public address system which may obviously be used in any location either indoors or outdoors and where no electric current is available.

While the parts constituting the amplifying apparatus are of conventional construction, the mounting of said parts on and in conjunction with the harness 16 constitutes a part of the novel combination.

Various modifications and changes are contemplated and may obviously be resorted to, without departing from the spirit or scope of the invention as hereinafter defined by the appended claims.

I claim as my invention:

1. A portable self-contained amplifier comprising a detachable body engaging harness including a waist encircling member and shoulder engaging straps, rigid supporting means constituting a substantially upright rear portion of said harness connected to and supported by the rear portion of said waist encircling member and to which said shoulder engaging straps are connected, an amplifier, means detachably suspending said amplifier from said rigid supporting means, a standard secured to and rising from the upper portion of said rigid supporting means, a loud speaker mounted on the upper end of said standard and substantially above the level of the upper portion of said harness and electrically connected to the amplifier, a microphone electrically connected to the amplifier, a neck engaging loop detachably supporting said microphone, a battery supplying electric current to the amplifier and detachably connected thereto, and a sling supporting said battery and detachably supported by the harness.

2. A portable self-contained public address system as in claim 1, a control panel, means detachably mounting said control panel on a front portion of said harness, said control panel having portions electrically connected to the amplifier including posts to which the battery is detachably connected, a make and break switch mounted on said panel and controlling the supply of current to the amplifier from the battery, and a volume control unit mounted on the panel and electrically connected to the amplifier including a manually operative volume regulating knob.

3. A portable public address system as in claim 1, electrical connections between the loud speaker and amplifier and the microphone and amplifier

including electric plugs detachably connected to said amplifier, and means mounting said loud speaker on said standard for swingably and turnably adjusting the loud speaker relatively to the standard.

4. A portable public address system as in claim 1, said rigid supporting means including inwardly bowed back engaging portions, and cushioning members enclosing said inwardly bowed back engaging portions.

5. A portable public address system as in claim 1, said harness including substantially rigid side brace members fixed to and extending upwardly from side portions of the waist encircling member having inwardly bowed intermediate portions, and cushioning means enclosing said rigid side brace members.

6. A portable public address system as in claim 5, said waist encircling member including a rigid section defining the back and side portions thereof and to which said side brace members and rigid supporting means are secured, and cushioning means disposed on the inner side of said rigid waist encircling section.

7. A portable public address system comprising a waist and shoulder engaging harness having a rigid rear waist engaging and back engaging portion, an amplifying unit, means detachably mounting said amplifying unit on said rigid rear harness portion, a standard fixed to and rising from the upper end of said rigid rear harness portion, a loud speaker adjustably supported on the upper end of said standard substantially above the level of the upper end of the harness and electrically connected to said amplifier, a microphone electrically connected to the amplifier, a neck engaging loop connected to and supporting said microphone, a self-contained current source electrically connected to the amplifier, and means demountably supporting said current source on said harness.

8. A portable public address system as in claim 7, a control panel electrically connected to the amplifier including a shutoff switch and a volume control, and means detachably mounting said control panel on a front portion of the harness.

9. A portable public address system comprising a waist and shoulder engaging harness having a rigid rear waist engaging and back engaging portion, an amplifying unit, means detachably mounting said amplifying unit on said rigid rear harness portion, a standard fixed to and rising from the upper end of said rigid rear harness portion, a loud speaker adjustably supported on the upper end of said standard substantially above the level of the upper end of the harness and electrically connected to said amplifier, a microphone electrically connected to the amplifier, a self-contained current source electrically connected to the amplifier, and means demountably supporting said current source on said harness.
